PANTY GIRDLE

Josie Gentile, Somerset, N.J., assignor to Maidenform, Inc., New York, N.Y.

Filed May 31, 1973, Ser. No. 365,434

Term of patent 7 years

Int. Cl. D2—01

U.S. Cl. D2—4

FIG. 1.

FIG. 2.

FIG. 1 is a front elevational view of a panty girdle showing my new design, the back being conventional; and FIG. 2 is a front elevational view thereof in the inside out position.

I claim:

The ornamental design for a panty girdle, as shown and described.
